BY MESNE ASSIGNMENTS, TO THE LUFKIN RULE CO., OF SAGINAW, MICHIGAN, A
CORPORATION OF MICHIGAN.

TAPE CASE AND WINDING-DRUM.

1,105,579.

Specification of Letters Patent.

Patented July 28, 1914.

Application filed July 26, 1913. Serial No. 781,345.

To all whom it may concern:

Be it known that we, GEORGE F. PUTNAM and HENRY H. WESSENDORFF, respectively citizens of the United States and Germany, 5 residing at the city of Flint, county of Genesee, State of Michigan, have invented a certain new and useful Improvement in Tape Cases and Winding-Drums, and declare the following to be a full, clear, and exact description of the same, such as will enable others skilled in the art to which it pertains to make and use the same, reference being had to the accompanying drawings, which form a part of this specification.

15 This invention relates to tape cases and drums and has for its object a drum whose rotative bearing upon the case is wholly on one side of the case.

In the drawings: Figure 1, is a cross section of the parts in position for assembly. 20 Fig. 2, is a cross section of the tape case and drum assembled. Fig. 3, is an interior plan view of the drum and the half of the case that holds the drum.

25 The tape-case is composed of two halves *a*, *b*. On one half the metal of the face is turned in as at *c* to receive the drum *d*. Each half of the case is notched to form an opening *e* through which the tape emerges.

30 The drum *d* may be of any desired construction. We have shown a drum which has a pivoted crank *f* with a handle *g*. This handle may be passed through the hole *h* in the end of the drum and held in the interior 35 of the drum by the spring *i*. A "knockout" handle, that is, a handle and a crank which are forced outward by pressing or releasing a member might be used in connection with the drum. The drum has two slots *j* in its

40 side walls for the reception of the cross strip *k* which is attached to the ring *l*. The ring and the cross strip form a bearing that is journaled wholly in one side of the case by turning the lip *c* (Fig. 1) back upon the ring 45 *l* (Fig. 2). At the center, the cross strip *k* has an aperture *m* that is screw-threaded. After the bearing unit has been placed, it remains permanently *in situ*. A small screw *n* passes through the center of the end of the

50 drum and engages with the screw-threads of the aperture *m* to fasten the drum to the bearing unit. It will be noted that this screw is under the crank *f* when the crank is held against the end of the drum, as shown

in Fig. 2. Hence the screw is not exposed 55 when in the pocket or being carried about so that it can be turned out of place and lost. This is one of the main objections to the old form of construction in which the screw was located on the opposite side of the case. 60

Our invention does away with the central post and allows a perfect plain face on one side of the case.

What we claim is:

1. The combination with a tape case provided on one side with a central opening and a turned-in lip, of a bearing unit journaled wholly in one side of the case by doubling the turned-in lip upon the bearing unit and a drum fastened to the bearing unit, substantially as described. 65

2. The combination with a tape case having a side wall provided with a central opening, of a bearing unit journaled wholly in one side of the case, a tape drum exposed 75 only at the side of the case that journals the bearing unit, a screw for removably fastening the tape drum at its exposed end to the bearing unit so that when the drum is detached from the bearing unit the drum 80 may be removed through the central opening, and a crank for turning the drum pivoted to the drum and arranged to overlie the screw when the crank is held against the drum in closed relation, substantially as described. 85

3. The combination with a tape case provided with a turned-in lip, of a bearing unit journaled wholly in one side of the case, comprising a ring rotatably held by said lip 90 and a cross strip with a threaded central aperture, a drum notched on the sides to straddle the cross strip and a screw passed through the end of the drum and adapted to run into the threads of the aperture of the 95 cross strip, substantially as described.

4. The combination, with a tape case having only two side walls and a peripheral inclosure, one of the side walls being provided with a central opening, of a tape drum passing through said central opening and terminating short of passing into the opposite side wall, and means for journaling and supporting said tape drum wholly upon the side wall through which it passes. 100

5. The combination of a tape case comprising only two side walls and a peripheral inclosure, one of the side walls being pro-

vided with a central opening, of a tape drum
passing through said central opening and
terminating short of passing into the oppo-
site side wall, a bearing unit journaled
5 wholly within the side wall through which
the drum passes and adjacent the said cen-
tral opening, and a fastening device for de-
tachably connecting the bearing unit and
the drum, said fastening device being ex-
10 posed at the outside so that it may be oper-

ated to disconnect the drum and the bearing
unit without disassembling the tape case.

In testimony whereof, we sign this specifi-
cation in the presence of two witnesses.

GEORGE F. PUTNAM.
HENRY H. WESSENDORFF.
